UNITED STATES PATENT OFFICE.

JOHN H. ELFERING, OF CAMDEN, NEW JERSEY, ASSIGNOR TO VICTOR TALKING MACHINE COMPANY, A CORPORATION OF NEW JERSEY.

SOUND-BOX DIAPHRAGM.

1,182,078.

Specification of Letters Patent.

Patented May 9, 1916.

Application filed November 12, 1910. Serial No. 591,947.

To all whom it may concern:

Be it known that I, JOHN H. ELFERING, a citizen of the United States, and a resident of Camden, in the county of Camden and 5 State of New Jersey, have invented certain new and useful Improvements in Sound-Box Diaphragms, whereof the following is a specification, reference being had to the accompanying drawing.

10 This invention particularly relates to diaphragms for sound recording and reproducing devices, such as are preferably adapted to talking machines.

The principal object of this invention is to 15 provide a diaphragm that will readily respond to the most delicate vibrations and accurately record and reproduce all of the high and low tones and the included range with equal clearness.

20 Further objects of this invention are to provide a diaphragm having its major portion formed substantially inflexible and capable of reciprocation independently of its margin; and to provide means to flexibly 25 connect said inflexible major portion with said margin.

The form of this invention hereinafter described provides a diaphragm comprising a central conically dished inflexible plate, having 30 a peripheral flange extended in a plane in substantially perpendicular relation to the axis of said conical plate, a separate annular margin surrounding said flange in a plane therewith, and a thin flexible imperforable 35 membrane connecting said flange and margin and arranged to support said inflexible plate.

This invention further includes all of the 40 various novel features of construction and arrangement hereinafter more definitely specified.

In the accompanying drawing Figure 1 is a front elevational view of a diaphragm showing the preferred embodiment of this 45 invention; Fig. 2 is a central transverse sectional view taken on the line 2-2 in Fig. 1; Fig. 3 is a front elevational view of a modification of the structure shown in Fig. 1; and Fig. 4 is a transverse sectional view of 50 the diaphragm shown in Fig. 3 and taken on the line 4-4 in said figure.

In the form of this invention shown in 55 Figs. 1 and 2 the central major portion of the diaphragm comprises the conically dished disk or plate 5, which as best shown

in Fig. 2 has the peripheral flange 6 extended in a plane in perpendicular relation to the axis of said diaphragm and surrounded by the annular marginal member 8 in spaced relation to the periphery of said flange 6, and 60 in a plane therewith. Said marginal member 8 is connected with the flange 6 by a thin membrane 10, which may be formed by any suitable imperforable flexible material, preferably gold beater's skin, and which may be 65 conveniently secured to said connected members by any suitable adhesive material. Said membrane 10 is arranged to support the central conical plate 5 in reciprocatory relation to the marginal member 8 which may be 70 suitably secured in a sound box of any convenient construction.

It may be here noted that the diaphragm may be formed of any suitable material 75 preferably paper or other fibrous material which may be treated with a resinous solution or other convenient material to render it impervious to any atmospheric conditions or moisture or may be formed of any stiff sheet material.

The form of this invention shown in Figs. 3 and 4, provides a diaphragm similar to the diaphragm shown in Figs. 1 and 2, and comprises the rigid central portion forming the 80 conically dished plate 14 which is connected by the narrow webs or spokes 15 with a sound box engaging marginal portion 16, forming the arc-shaped apertures 18, which are local to the periphery of said diaphragm, and which permit the free relative vibration 85 of the central portion or plate 14, with respect to the marginal portion 16 to which it is connected by the flexible membrane 20. As best shown in Figs. 1 and 3, the central 90 plates 5 and 14 are respectively provided with apertures 22, for the convenient attachment of a stylus bar (not shown) which may be co-operative therewith to record and 95 reproduce sound.

It is well known that in diaphragms 100 wherein the margin is engaged in a sound box, and the intermediate portion is free to vibrate to reproduce sound, the central portion which is connected with the stylus bar is afforded the maximum vibration, while 105 the surface intermediate of the central portion and the periphery vibrates with varying force diminishing toward the margin of the diaphragm which is engaged. Therefore it will be readily observed that a diaphragm 110

constructed in accordance with this invention is advantageous in that the major portion is substantially inflexible, and is reciprocated bodily, thus vibrating substantially uniformly throughout its extent, and consequently the compression and rarefaction of the air in the sound conveyer due to the vibration of said diaphragm is uniform throughout its extent.

10 It is not desired to limit this invention to the precise details of construction and arrangement herein set forth, as it is obvious that various modifications may be made therein without departing from the essential 15 features of the invention as defined in the appended claims.

Having thus described my invention, I claim:

1. A diaphragm having a substantially rigid major central portion, a marginal portion connected thereto by relatively narrow

flexible radial sections, and a flexible concentric membrane intermediate of said central and said marginal portions.

2. A diaphragm having a rigid major central portion connected with a marginal portion by integral relatively narrow flexible radial sections and a flexible web connecting said central portion and marginal portion together.

3. A diaphragm comprising a central comparatively rigid conical dished major portion, a surrounding portion and a plurality of radial webs and an annular web connecting said portions.

In witness whereof I have hereunto set my hand and seal this 9th day of November A. D. 1910.

JOHN H. ELFERING. [L. S.]
